United States Patent

Des. 241,748

Patented Oct. 5, 1976

241,748

PORTABLE TREE PLATFORM

James H. Bakken, 1640 Haze St.,
Madison, Wis. 53704

Filed Dec. 1, 1975, Ser. No. 636,760

Term of patent 14 years

Int. Cl. D25—99
U.S. Cl. D25—62

FIG. 1

FIG. 2

FIG. 3

FIG. 4

FIG. 5

FIG. 6

FIG. 7

FIG. 1 is an isometric view of a portable tree platform, with a rope used for attachment to a tree shown in broken lines for illustrative purposes only.

FIG. 2 is a rear elevational view thereof.

FIG. 3 is a top plan view thereof.

FIG. 4 is a bottom plan view thereof.

FIG. 5 is a side elevational view thereof.

FIG. 6 is a side elevational view thereof opposite to that shown in FIG. 5.

FIG. 7 is a front elevational view thereof.

I claim:

The ornamental design for a portable tree platform, as shown and described.
